CLAIM

The ornamental design for a light, as shown and described.

DESCRIPTION

FIG. 1 is a perspective view of a light showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines illustrate portions of the light which form no part of the claimed design.

The drawings include surface shading which illustrates contour and not surface ornamentation.
